US00D743819S

(12) **United States Design Patent**
Golnik et al.

(10) **Patent No.:** US D743,819 S
(45) **Date of Patent:** ** Nov. 24, 2015

(54) **ACTIVITY MONITORING DEVICE**

(71) Applicant: **Misfit Wearables Corporation**, Salem, NH (US)

(72) Inventors: **Tim Golnik**, San Francisco, CA (US); **James Toggweiler**, San Francisco, CA (US)

(73) Assignee: **Misfit Wearables Corporation**, Salem, NH (US)

(**) Term: **14 Years**

(21) Appl. No.: **29/512,056**

(22) Filed: **Dec. 16, 2014**

(51) LOC (10) Cl. **10-04**

(52) U.S. Cl. **D10/70**
USPC ....
